PORTABLE GAME PLAYING DEVICE UTILIZ-
ING BALLS SIMULATING PLAYING CARDS

John J. Hickey, Belleville, N. J.

Application March 21, 1947, Serial No. 736,150

4 Claims. (Cl. 273—148)

1

This invention relates to games and refers more particularly to improvements in machines designed to shuffle and serve balls bearing the insignia of playing cards.

My Patent No. 2,334,093, issued November 9, 1943, relating to a machine for playing solitaire and similar games, comprises a hollow drum capable of being rotated at an angle to the horizontal for the shuffling of rotary elements serving as substitutes for playing cards, and a swingable element disposed therein for lifting the mixed rotary elements from the hollow drum and serving them to players. My Patent No. 2,383,860, issued August 28, 1945, covering improvements in the aforesaid machine, comprises an inclined plane disposed in a hollow body, the plane being formed of a winged central portion which when elevated together with the arcuate surface portion of the interior of the hollow body constitutes the shuffling chamber. When the movable section of the plane is brought into alignment with the other portions thereof, channels guide the mixed balls in serving the players with representations of cards, dealt face upward, or downward, dependent upon the direction in which the hollow body is tipped.

It is an object of the instant invention to provide a portable machine for shuffling and dealing in simulated card games that will aid still further in the social rehabilitation of the less fortunate members of the community who have lost their ability to handle ordinary playing cards but who still may derive stimulation from the games.

Another object is to provide a machine that will shuffle or mix and deal or serve in any simulated card game requiring one or more regular packs of playing cards.

Still another object is to make simulated card games possible under conditions that would prohibit the use of the ordinary pasteboard playing cards.

It is also an object of this invention to provide a machine that will provide simulated card games based on the laws of chance without arousing suspicion among contestants.

Other objects will become apparent in the course of the following specification when taken in conjunction with the accompanying drawings which show a preferred embodiment thereof and in which like reference numerals indicate like parts.

In the attainment of these objectives, it has been found advisable to so form the machine that it will simulate the principal steps in card games,

that is, holding or containing and mixing or shuffling a large number of playing units; repeatedly allocating and dealing to the players small lots of the required predetermined numbers of mixed playing units; displaying or concealing the mixed and dealt units in partially completed and wholly completed hands; and returning the discarded playing units to storage or for further mixing as desired. In the accomplishment of these sequential steps, a semi-rotatable mixing component is disposed in a casing equipped with a ball displaying tray for exposed hands, and ball-concealing box pockets for unexposed hands. Balls marked to represent cards of the deck are inserted in the semi-rotatable mixing drum and tossed about therein by clockwise and counter-clockwise movements thereof until mixed. An allocating chamber or device inserted in the mixing drum segregates the balls that are to be served. A counter-clockwise movement and contact of the drum with a stop, deposits the balls by centrifugal force on an adjustable runway to the ball-displaying tray for the exposed hand, to the ball-concealing box pockets for the unexposed hands, or back into the mixing drum as desired.

The device is particularly adapted for playing with balls such games as stud poker where all cards but the first round are dealt face up and the betting usually begins after the first round. However, a number of other games may be played by means of the same machine. The number of contestants may be increased or decreased as desired. With the exception of the relatively minor operation of mixing the balls, little physical effort of any kind is required.

35 In the drawings:

Figure 1 is a view in perspective of the game-playing device constructed in accordance with the principles of the present invention.

40 Figure 2 is a longitudinal horizontal section through the line 2—2 of Figure 1.

Figure 3 is a longitudinal vertical section through the line 3—3 of Figure 1.

45 Figure 4 is a longitudinal horizontal section through the line 4—4 of Figure 1.

Figure 5 is a horizontal sectional view through the line 5—5 of Figure 3.

Figure 6 is a top view of the ball-displaying tray enlarged.

50 Figure 7 is an end view of the ball-displaying tray shown in Figure 6.

Figure 8 is an enlarged top view of the lever controlling the serving of the balls to the ball-displaying tray, ball-concealing box pockets, or 55 back into the mixing drum.

Figure 9 is a side view of the lever shown in Figure 8 with part of the casing removed.

Figure 10 is a view in perspective of the ball concealing box pocket.

The game playing machine comprises the casing 10, the detachable ball-displaying tray 11, and the ball-concealing box pockets 12.

The casing 10 supports the hollow semi-rotatable drum 13 (Fig. 3), and subsequently described associated means (Figs. 1, 2, 4 and 6) for serving the balls 14 to the ball-displaying tray 11 (Figs. 1, 6, and 11), in the ball-concealing box pockets 12 (Figs. 1, 3 and 10), or back into the drum 13, (Fig. 3). The casing may be constructed of any suitable material and of any shape with due regard to the rotation of the drum 13 (Fig. 3). In addition, it may be formed exclusively or partially of opaque materials as long as the secrecy of the unexposed hands is maintained.

The game is played with the balls 14 having an outside cover sufficiently resilient to suppress noise and relatively heavy cores to insure both thorough mixing and free rolling. The surfaces of the balls are further designed for durable imprinting of the card indicia so that wear and tear caused by repeated mixings and dealings is minimized. Moreover, the balls may be colored to conform to the four suits of the usual deck of playing cards.

The drum 13 is disposed in the casing 10 in such a manner that it can be rotated through substantially 180° by the handle 15 (Figs. 1 and 2) about the axis 16 (Fig. 3) and from either side of the casing. Thus, the operator may use either his left or right hand, for the most arduous part of the game. Shuffling is accomplished by moving the drum back and forth several times through some 180°. The drum 13 is formed of two circular discs, Figure 3, keyed to the axle 16 and separated from the sides of the casing and each other by spacing washers or similar means as required. The axle 16 is rotatably mounted through the spaced parallel members of the casing 10 by any suitable bearing means 16a and 16b. The circumference of the drum is covered except for the opening 17 (Fig. 3) at one end of which an allocating chamber 18 (Fig. 3) is located. The allocating chamber 18, disposed as shown between the rims of the drum, extends partially above the circumference thereof and comprises the outer compartment 19 and inner compartment 20 which are separated by a floor formed with the trap door 21, opening into the outer compartment 19, and the base of the receptacle 22. The floor of this receptacle, as well as the corresponding surface of the trap door, is provided with channels formed by the inserts 23 (Fig. 3) and having sufficient space for entrapping one ball in each stall in the herein-after described manner.

The machine illustrated provides one stall for each of five players but, of course, the number of stalls may be increased or decreased as desired. With the allocating chamber 18 in the down position, shown dotted in Figure 3, the trapdoor 21 will open, under its own weight as well as the weight of the inserted balls or other means as desired, and the balls will tend to fall through into the outer chamber 19 but not more than one can pass into each of the five stalls because of the limited swing of the trapdoor 21, that is, limited by an attached guide moving in the slot 40, the overhead surface portion 24, and the magnitude of the receptacle 22. Moving the drum counterclockwise, the rotatable

trapdoor will close of its own weight and the remainder of the balls pressing to pass through the trapdoor 21, will drop back into the mixing drum 13 for further mixing or shuffling against baffles (not shown) inserted within the drum against each other, and against the arcuate surface portion of the drum. The strip 39 between the rims of the drum will prevent the balls from rolling out the opening 17. When the allocating chamber 18 reaches the high point, shown solid in Figure 3, the impact with the stop 25, together with the downward inclination of the channels, will force the five entrapped balls out of the stalls, across aligned channels on the top surface portion of the trapdoor 21 and even aligned channels on the hinged portion of the platform 26 for ultimate distribution as later described. It is the semi-rotation of the drum between the low and high or nadir and zenith positions that causes the gravitational swinging of the trap door 21. At the nadir position, the trap door will be in the position shown by the dot and dash line of Figure 3. At the nadir position and during at least the first 90° of upward semi-rotation of the drum, one side of the trap door forms an inclined plane that will guide the balls into the stalls to the extent of the capacity thereof. During the upward cycle of the semi-rotation and above the 90° point, the door will drop by gravity to impose the other side of the trap door as an inclined plane, at and slightly beyond the zenith position, to guide the balls out of the stalls for disposition as desired.

The disposition of the balls at this point will depend upon the desire of the operator who by means of the lever 27 (Fig. 9) controlling the position of the hinged portion of the platform 26 may so regulate the latter that the balls may be returned to the mixing drum 13 or to the herein-after described ball-displaying tray 11 (Figs. 1, 6 and 7), or the ball-concealing box pockets 12 (Figs. 1, 3 and 10). With the lever 27 (Figs. 8 and 9) set at the "mix" position, Figure 8, the outer end of the hinged portion of the platform 26 will be rotated to the upper dot dash position shown in Figure 3. With the allocating chamber 18 revolved to the zenith position shown in Figure 3, the balls in the channels of the outer compartment 19 will roll by gravity out of the chamber and will be held by the hinged end of the hinged portion of the platform 26 in a position or trough 31. However, as soon as the drum is rotated clockwise, the balls in the trough 31 prevented from rolling down the platform 26 or back into the chamber 18 because of the oppositely inclined surfaces will fall downwardly by gravity. The rim of the drum 13 being open forwardly of the chamber 18 and under the position 31 in the zenith position of the chamber 18, the balls caught between the hinged end of the hinged portion of the platform and the chamber will fall through the drum opening. Since a too rapid clockwise rotation relative to the magnitude of the opening 17 might deflect some of the balls out of the drum, a radially directed partition 16d is disposed on the drum between the axis 16 and the end of the opening 17 adjacent the chamber 18. The outer portion 16c of the partition 16d is hinged adjacent the axis in such a manner that it will rotate under gravity counterclockwise as illustrated in Figure 3 in the zenith position of the chamber to provide a guideway back into the drum for the balls falling through the opening 17. With the chamber 18 in the down position shown by the dot dash lines in Figure 3,

the hinged portion 16c of the partition will also by gravity and the coaction of the hinges form a straight angle as illustrated. With the lever 27 (Fig. 8) set at the "up deal" position, the channels 28 (Figs. 1 and 2) of the ramp or hinged portion of the platform 26 (Figs. 2 and 3) will be aligned with the channels 29 of the ball-displaying tray 11 (Figs. 1, 3 and 6). With the lever 27 set at the "down deal" position, Figure 8, the channels 28 (Fig. 1) of the ramp 26, shown in lowest dotted position in Figure 3, will be aligned with the channels 30 (Fig. 4) to the ball concealing box-pockets 12.

The ball-displaying tray 11 is removably attached to one end of the casing 10 by the supports 32 inserted over the studs 33. As attached, the plane of the top surface portion or upper deck having the channels 29 aligned with the channels 28 of the ramp 26 is set at less than 90° to the casing in order that the balls will freely run out thereon. The first balls out will come in contact with the gate 35 and the subsequently dealt balls will be aligned in grooves in back of these until the channels are filled as desired. By moving the gate 35 upward, the balls will be released through the transverse opening 11a at the lower end, and will fall onto the lower deck or bottom member 36 of the tray 11 either for storage purposes or for return to the mixing drum dependent upon whether or not the hinged partition 37 actuated by the handle 38 is open or closed. When the handle 38 is in the down or closed position, the balls released by the gate 35 will be entrapped on the bottom member or base 36 of the tray. Thus, these entrapped balls will represent the used or discarded portion of the card deck. The remainder of the balls in the mixing drum, representing the unused portion of the deck, may continue to be served in the manner previously shown. By moving the handle 38 to the open position, the balls will fall back into the mixing drum after passing over the platform 34 (Figs. 3 and 5) through the opening 17 for further dealing as required. When not in use, the tray may be detached and stored in the casing.

Where it is desired to serve or deal an unexposed hand, the movable platform lever 27 is moved to the "down deal" position whereupon the balls rolling down the channels 28 of the platform 26 will follow the aligned channels 30, Figure 4, leading to the five ball-concealing box pockets 12. The box pockets 12, two of which are located on either side of the casing and one in the front, are of tunnel shape adjustably attached to the casing so that an opening in the pocket will fit over a corresponding opening in the casing. The pocket is of such depth that the ball is visible only to the player who has removed the pocket. As in the case of the tray, when the box-pockets are not in use, they may be stored also in the casing.

The channels of the ball displaying tray may be numbered consecutively and the box pockets marked by corresponding numbers. A player in a game of stud poker, having elected to use channel No. 1 or 2, etc. with its correspondingly numbered box pocket, can receive his unconcealed or "face up" playing units dealt into his numbered channel and his concealed or "face down" playing units in his supplementary box pocket.

It is apparent that the invention shown above has been given by way of illustration and not by way of limitation and that the above described machine is subject to wide variations and modi-

fications without departing from the scope or intent of the present invention. All of such variations and modifications are to be included within the scope of the present invention.

5. What is claimed is:

1. A portable device for the mechanical playing of simulated card games wherein the cards are replaced by balls carrying card indicia, the device comprising a casing, a downwardly and outwardly directed platform secured to an inner wall of the casing, the casing having an opening formed therein, the platform having at least one longitudinal channel formed thereon and adapted to guide the balls through said opening out of the casing; the apparatus further comprising a mixing drum for the balls rotatably disposed in the casing, the drum having an opening formed in the rim thereof; the mixing drum further comprising an allocating chamber disposed at one end of the drum opening, a floor disposed in the chamber substantially along the periphery of the drum dividing the chamber into an inner and an outer compartment, said floor being adapted to be moved into a position wherein it is substantially in alignment with said platform, the inner compartment communicating with the interior of the drum and the outer compartment having an open end adjacent the opening in the rim of the drum, a trap door hingedly disposed in the floor at the open end of the outer compartment and opening therein, the floor having a channel formed thereon and adapted to be aligned with the channel on the platform.

2. A portable device for the mechanical playing of simulated card games wherein the cards are replaced by balls carrying card indicia, the device comprising a casing, a downwardly and outwardly directed platform secured to an inner wall of the casing, the casing having an opening formed therein, the platform having at least one longitudinal channel formed thereon and adapted to guide the balls through said opening out of the casing; the apparatus further comprising a mixing drum for the balls rotatably disposed in the casing, the drum having sides extending parallel to the longitudinal center line of the platform and equally spaced on either side thereof, and a rim having an opening formed therein; the mixing drum further comprising an allocating chamber disposed at one end of the rim opening and extending above the periphery of the drum, a floor disposed in the allocating chamber dividing the chamber into an inner and an outer compartment substantially along the periphery of the drum, the inner compartment communicating with the interior of the drum and adapted to entrap at least one ball in the down position of the chamber, the floor having at least one channel on the side of the outer compartment adapted to be aligned with the channel on the platform in a predetermined position of the drum, and a trap door hingedly disposed in the floor and adapted to pass at least one ball from the inner to the outer compartment when the chamber is in the down position.

3. A portable device for the mechanical playing of simulated card games wherein the cards are replaced by balls carrying card indicia, the device comprising a casing, a platform secured to an inner wall of the casing, the casing having an opening formed therein, the platform being outwardly and downwardly inclined and adapted to display the balls emerging through said opening at the front of the casing, the back portion of

the platform being hinged and adapted to rotate the outer edge of the hinged portion upwardly above the plane of the platform and downwardly below the plane thereof, the platform having at least one channel formed thereon and adapted to guide the balls out of the casing when the hinged portion is in the plane of the platform; the apparatus further comprising a mixing drum for the balls rotatably disposed in the casing, the drum having sides equally spaced on either side of the longitudinal center line of the platform, and a rim having an opening formed therein; the mixing drum further comprising an allocating chamber disposed at one end of the rim opening and extending thereabove, a floor disposed in the allocating chamber substantially along the rim of the drum, the floor dividing the chamber into an inner and outer compartment, the inner compartment being adapted to entrap at least one ball when the chamber is rotated to the down position, the outer compartment having an open end adapted to be aligned with the hinged end of the platform when the hinged end is in the plane of the platform, the hinged end interrupting the connection between the outer compartment and the platform when the hinged end is in its upward and downward positions, said casing having a pocket formed therein for receiving balls from said hinged end in the downward position thereof, the floor having at least one longitudinal channel on the side of the outer compartment,

a trap door hingedly disposed in the floor at the open end of the outer compartment and adapted to pass the ball entrapped in the inner compartment to the outer compartment in the down position of the chamber, and means returning the ball from the hinged end of the platform in the up position thereof to the drum.

4. A portable device for the mechanical playing of simulated card games according to claim 3 in which the means returning the ball from the hinged end of the platform in the up position thereof to the drum comprises a partition radially disposed in the drum and aligned with the hinged end of the platform in the up position of the chamber, said device further comprising a trap door hingedly disposed in the inner end of the partition and opening outwardly toward the opening in the rim of the drum under gravity in the up position of the chamber.
